PATENTED DEC. 25, 1906.

E. O. BENNETT.

APPARATUS FOR REMOVING SUPERFLUOUS BRONZE.

APPLICATION FILED MAR. 22, 1906.

UNITED STATES PATENT OFFICE.

EDWARD O. BENNETT, OF SAN FRANCISCO, CALIFORNIA, ASSIGNOR OF ONE-HALF TO ILLINOIS PACIFIC GLASS COMPANY, OF SAN FRANCISCO, CALIFORNIA, A CORPORATION OF CALIFORNIA.

APPARATUS FOR REMOVING SUPERFLUOUS BRONZE.

No. 839,704.

Specification of Letters Patent.

Patented Dec. 25, 1906.

Application filed March 22, 1906. Serial No. 307,422.

To all whom it may concern:

Be it known that I, EDWARD O. BENNETT, a citizen of the United States, residing in the city and county of San Francisco and State 5 of California, have invented new and useful Improvements in Apparatus for Removing Superfluous Bronze, of which the following is a specification.

My invention relates to bronzing-machines, 10 and especially pertains to a pneumatic appliance for removing superfluous bronze.

It is common in the printer's art in bronzing paper and the like, to apply a size first to the article to be bronzed; then to pass the 15 sized article through a so-called "bronzing-machine" to apply and set the bronze and to remove some of the superfluous bronze; the final operation is the passage of the bronzed article again through the machine (the feed 20 of bronze having been discontinued and the deposits of bronze in the machine removed) to remove the balance of superfluous bronze.

The main object of my invention is to do away with the necessity of thus having to 25 pass the paper through the machine a second time and to bronze the paper and remove all the superfluous bronze from the paper, from the machine, and from the room at one operation.

30 The present method is objectionable in other ways besides that of having to handle the paper so many times. Although the bronzing and bronze-removing mechanisms are carefully incased, the bronze-powder is in the nature of a very fine impalpable dust that sifts out through various cracks and crevices and goes floating through the air to be deposited all over the printing-shop to the great annoyance and discomfort of the employees, damage to stock, &c. Besides, those 35 who are working immediately over the machines are required to use sponges or other respiratory apparatus to exclude the poisonous dust from their lungs.

40 A great amount of money and much thought have been expended in endeavoring to overcome the various objections above noted; but with many years' experience I have yet to know of means other than that 45 which I am about to describe which have proven successful.

My invention consists of the parts and the

construction and the combination of parts, as hereinafter more fully described and claimed, having reference to the accompanying drawings, in which—

Figure 1 is a sectional view of a well-known type of bronzing-machine to which my invention has been applied. Fig. 2 is a plan view of the same.

Referring to the drawings, A represents the frame of a well-known type of bronzing-machine, as seen, for example, in Patent No. 613,412, November 1, 1898. This machine has the usual rotary cylinder or paper-carrier 2, feed-table 3, grippers 3', bronze-feed hopper 4, distributing-rollers 5, rotary buffering and bronzing pads 6, dusting-rollers 8 9 10, casing 11, with hinged doors 12 12' for the bronzing and dusting mechanisms, respective horizontal partitions 13 14 between rollers 8 9, 9 10, brushes 15, strippers 16, and discharge 16'. Rollers 8 9 revolve in a reverse direction to cylinder 2 and operate to remove the major portion of the excess 75 bronze from the paper. Roller 10 revolves with the cylinder and is in the nature of a cleansing-roller. The dust raised by the rollers is deposited (such as does not escape into the room) within the machine and is removed therefrom generally by mechanical means.

My invention may be said to comprehend the exhausting by steady and regulated flow, the air that may come in contact with the 85 bronzed surface of the material while the same is passing through the machine, and thus carry off all dust whatsoever removed from the paper by the dusting brushes or rolls. In accomplishing this it is very essential that very little draft or irregular air-currents be produced, as the same greatly interferes with the feeding and handling of the paper. In order to obtain these results, I preferably employ air-conductors of peculiar construction and connect the same to the different compartments containing the bronze-applying and dusting attachments of the machine so that the flow of air may be regulated to suit the different positions the 90 paper may be in as it passes through the machine. For instance, the current of air should be very light or simply strong enough to carry off the finest particles while the bronze

is being applied, then much stronger as the dusting or rubbing off is being done, and, finally, the air-currents should be very much reduced again after the grippers on the carrier release the paper, else the delivery and carrying away of the paper will be more or less seriously interfered with. If too strong a suction is exerted in the earlier stages of the bronzing process, the bronze is likely to be disturbed on the paper before it has had ample time to set and will result in smudging the paper and rendering the work streaky.

In carrying out my invention I employ suction apparatus of suitable construction—as, for example, the fan 17, which may be operated by any appropriate means, as the motor 18. This fan has an induction-trunk 19, connected with the interior of the casing 11, and an eduction-trunk 20, which is adapted to connect with any suitable chamber or means for collecting the dust sucked up by the fan. The lower end of the trunk 19 has a removable section 19', which latter has separately-valved branches connecting with the respective compartments in which the dusting-brushes are located, and the parts are arranged and connected in such fashion as to permit ready access to any of said compartments.

As here shown, the partitions 13 14 divide the casing into three compartments 21 22 23. Manifestly there could be more partitions and more compartments, in which case there would be more branches leading to trunk 19. The trunk-section 19' has a branch 24, connecting with the upper compartment 21, a second branch 25, connecting with the compartment 22, and a third branch 26, connecting with the lowermost compartment 23. The door 12^a, which gives access to all of the compartments 21 22 23, is shown as hinged at 12' and as comprising two plates standing in different planes and connected rigidly together by the branches 24 25 26 and trunk-section 19'. When door 12^a is opened, all of said parts drop down as a unitary structure. When the door is closed and locked, the abutting ends of the trunk 19 and 19' are brought together in tight joint and locked by suitable means, as indicated at 27. The door-plates also fit snug and dust-proof around the edges of the compartments and are held tight by suitable means, as the cam-hooks 28. The bottom of the section 19' is provided with a gate or valve 19^a, by which the dust deposits in the section may be withdrawn from time to time. Ordinarily valve 19^a would be closed, so that the circulation of air takes place only through the branches 24 25 26. Each branch 24 25 26 is provided with a suitable valve 29, by which the air-currents passing through the several branches may be separately controlled or regulated and the force of the suction in the

several chambers 21 22 23 varied and regulated to suit requirements and for the reasons hereinbefore enumerated.

In order to prevent air being drawn in around the edges of the paper on the cylinder, I provide a suitable opening or openings 30 in the bottom of the lower compartment 23, through which sufficient air for that compartment is admitted, and so avoid any suction on the discharge end of the sheet. The air entering at 30 circulates around back of roller 10 and around the edges of the partitions 14 13 proximate to the bronze-surface of the paper. By thus admitting a suitable quantity of air into the casing and in a suitable manner and by properly controlling the suction through the several branches 26 25 24 I am able, as has been amply demonstrated in practice, to effectually remove in one operation all of the superfluous bronze from the paper and from the machine and at the same time prevent escape of dust from the machine and the consequent contamination of the outside air.

Having thus described my invention, what I claim, and desire to secure by Letters Patent, is—

1. In a bronzing-machine, the combination with a paper-carrier, bronzing mechanism and bronze-removing mechanism, of a casing for said bronze-removing mechanism, said casing divided into a plurality of compartments, air-conducting pipes leading from the several compartments, means for creating a suction in said pipes, and means for controlling the force of the suction in the several pipes.

2. A bronzing-machine having paper-carrying means, bronze-applying, bronze-removing and dusting compartments, respective bronze-applying, bronze-removing and dusting means in said compartments, hinged closures for said compartments, separate air-pipes connected with said closures and communicating with respective compartments, means for creating a suction in said air-pipes, and means for varying the force of the suction through said several pipes.

3. In a bronzing-machine, the combination of a sheet-carrier, bronze-applying means, superfluous bronze-removing means, means for delivering the paper from the carrier, a casing having a plurality of compartments housing said bronze-applying and superfluous-bronze-removing means, and means for creating a suction in said compartment to remove the superfluous bronze, and means for modifying the suction at the beginning and ending of the bronzing process.

4. In a bronzing-machine, the combination of a sheet-carrier, an incased mechanism for applying bronze to the sheet, said mechanism operative to apply the bronze and to remove the superfluous bronze from the sheet prior to the delivery of the latter from

the carrier, an air-induction mechanism to carry away from the casing the bronze removed from the sheet, and means to cause said air-induction mechanism to exert a lighter suction on the paper during the application of the bronze and during the period immediately preceding discharge from the carrier than during the intermediate period.

In testimony whereof I have hereunto set my hand in presence of two subscribing witnesses.

EDWARD O. BENNETT.
